WELT HAVING A POLYGONAL BEAD

John J. Walsh, St. Louis, and John J. Dudenhofen, St. Clair, Mo., assignors of three-fourths to said Dudenhofen and one-fourth to George R. Ericson, Kirkwood, Mo.

Application May 4, 1950, Serial No. 159,886

2 Claims. (Cl. 36—78)

1
This invention relates in general to certain new and useful improvements in welts.

The primary object of the present invention is to provide a shoe which is attractive in appearance and simple in construction.

It is another object of the present invention to provide a shoe which is extremely flexible when on the foot of the wearer and yet gives the appearance of having an extremely thick sole.

It is another object of the present invention to provide a highly fashionable shoe which is attractive in appearance and is comfortable and long-wearing.

It is another object of the present invention to provide a slip-lasted shoe having a unique form of welt construction which gives the appearance of substantial sole thickness while at the same time providing an unusually great degree of flexibility.

With the above and other objects in view, our invention resides in the novel features of form, construction, arrangement, and combination of parts presently described and pointed out in the claims.

In the accompanying drawings (two sheets)—
Figure 1 is a plan view of the upper prior to stitching;

Figure 2 is a plan view of the sole or sock lining prior to stitching;

Figure 3 is a plan view of the heel insert prior to stitching;

Figure 4 is a plan view of the heel insert lining prior to stitching;

Figure 5 is a perspective view of the upper-forming elements stitched together prior to lasting;

Figures 6 and 7 are fragmentary sectional views taken along lines 6—6 and 7—7, respectively, of Figure 5;

Figure 8 is a side elevational view of the upper mounted upon a last;

Figure 9 is a perspective view of a welt strip forming a part of the present invention;

Figure 10 is a transverse sectional view of the welt strip taken along line 10—10 of Figure 9;

Figure 11 is a side elevational view of the upper mounted upon a last with the welt strip applied thereto;

Figure 12 is a sectional view taken along line 12—12 of Figure 11;

Figure 13 is a side elevational view of the finished shoe; and

Figure 14 is a sectional view taken along line 14—14 of Figure 13.

Referring now in more detail and by reference characters to the drawings which illustrate a pre-

ferred embodiment of the present invention, 1 designates a shoe upper which may be die-cut from suitable upper stock in the conventional manner. The upper 1 may be lined or unlined as desired. 2 designates a sock-lining which is also die-cut from suitable leather stock in the usual manner. Also die-cut from suitable leather stock are a heel insert 3 and a heel insert liner 4. The heel insert 3 is marginally seamed along its diverging margins *m* to the rear vertical margins *n* of the upper 1 and the heel insert liner 4 is stitched to the inside of the heel insert 3 and upper 1 to conceal the seam and provide a flat smooth interior face therefor, as shown in Figure 6. Thereupon, the sock-lining 2 is stitched to the margins of the upper 1, the heel insert 3, and heel liner 4 to form the completed upper A, as shown in Figure 5. It should be noted in this connection that the seam between the upper 1 and the sock-lining 2 is turned out to provide a relatively wide welt margin or flange *w*, as shown in Figure 7, and is secured by a double line of stitches 5, 6, the outer line of stitches being merely a preliminary or holding stitch and the inner line of stitching 5 being close to the interior limit of the shoe so that the upper A will ultimately hug the last securely and with proper conformity. The upper A is then slipped onto a wood last L, as shown in Figure 8, for receiving a welt strip 7, which is cut from a solid length of weltling stock and integrally includes a main body portion 8 provided along its inner face with an inwardly extending cove 9 and along its bottom face with a relatively wide laterally projecting flange 10, the upper face 11 of which is skived off, all as best seen in Figure 10. Preferably, the inside vertical face *f* of the weltling strip 7 is inclined inwardly and downwardly to fit the upper snugly. The ends of the weltling strip 7 are beveled in opposite directions so as to form a smooth lapped joint when the weltling strip 7 is disposed around the welt margin *w* of the upper A. The welt margin *w* of the upper A and the interior surfaces of the cove 9 of the weltling strip 7 are coated with a suitable adhesive and, thereupon, the weltling strip 7 is wrapped annularly around the welt margin *w* of the upper A and adhesively secured thereto by pressing the welt margin *w* tightly into the cove 9. It will be noted that in this connection that the cove 9 is sufficiently deep so as to snugly encase the welt margin *w* of the upper A, and the weltling strip 7 is pulled tightly around and back over along its beveled end margins to form a snug, tight, wrap-around fit, all as best seen in Figures 11 and 12.

Adhesively secured upon the under face of the

sock-lining 2 is a conventional sole filler 12 formed preferably of thin sheet cork, or other suitable material, and annularly skived around its peripheral margins to lap over and fit smoothly down upon the exposed inner face of the welt-ing strip flange 10, thus leveling the interior portion of the under side of the upper A.

The upwaardly presented faces (reference being had to Figure 12) of the lasted upper A and sole filler 12 and welt-ing strip flange 10 are suitably coated with adhesive and a conventional sole 13 applied thereto by appropriate pressure. The sole 13 is rounded to a pattern or shape which will register peripherally with the outer vertical faces of the welt-ing strip 7, and, finally, after the adhesive has set sufficiently to permit handling, the sole 13 is marginally secured by a continuous line of welt stitching 14, which extends through the entire body of the welt and sole 13, passing through the cove 9 and the welt-ing margin w of the upper A, so that the entire shoe is securely held together, substantially as shown in Figure 14. If desired, an additional heel flat 15 may be secured on the under face of the sole in any conventional manner, as shown in Figure 13.

It should be understood that changes and modifications in the form, construction, arrangement, and combination of the several parts of the shoe and method of making same may be made and substituted for those herein shown and described without departing from the nature and principle of our invention.

Having thus described our invention what we now claim and desire to secure by Letters Patent is—

1. A shoe welt comprising a bead of polygonal cross-sectional shape having a flat top face and flat oppositely presented lateral faces, said welt being of greater heighth than the width of the bead, said welt being undercut beneath the bead in the formation of a laterally opening cove having an upper face which is substantially parallel to the top face of the bead, and a relatively wide

skived flange extending laterally from the under-side of the cove the top face of said flange being substantially a continuation of the underface of the cove.

- 5 2. A shoe welt comprising a bead of polygonal cross-sectional shape having a flat top face and flat oppositely presented lateral faces, one of said lateral faces converging downwardly toward the other of said lateral faces so that the bead is somewhat narrower at the bottom than at the top, said welt furthermore being of greater heighth than the width of the bead, said welt being undercut beneath the bead in the formation of a laterally opening cove having an upper face of 10 which is substantially parallel to the top face of the bead, and a relatively wide skived flange extending laterally from the underside of the cove the top face of said flange being substantially a 15 continuation of the underface of the cove.

JOHN J. WALSH.
